UNITED STATES PATENT OFFICE.

MILTON H. SHOENBERG, OF SAN FRANCISCO, CALIFORNIA, ASSIGNOR TO MAJESTIC ELECTRIC DEVELOPMENT COMPANY, A CORPORATION OF CALIFORNIA.

ELECTRIC WATER-HEATER.

1,249,285.

Specification of Letters Patent.

Patented Dec. 4, 1917.

Application filed August 27, 1917. Serial No. 188,421.

To all whom it may concern:

Be it known that I, MILTON H. SHOENBERG, a citizen of the United States, residing at San Francisco, in the county of San Francisco and State of California, have invented certain new and useful Improvements in Electric Water-Heaters, of which the following is a specification.

My invention relates to electric heaters especially intended for heating water, but which may be adapted for other purposes.

One object of my invention is to provide a water heater which is exceedingly simple in construction and may be readily assembled and installed by unskilled labor. A further purpose is to provide a heating chamber which is entirely inclosed by electrodes through which an electrolytic action may be obtained without decomposition of the electrodes. Again it is my purpose to provide a heater which may be continuously connected to the source of electric current without endangering the electrodes and in which the flow of current will automatically cease when the water supply is shut off.

In the accompanying drawings, Figure 1 is a side elevation of a water heater embodying my invention and showing the manner of attaching it to a faucet; Fig. 2 is a vertical sectional view of the same; Fig. 3 is a vertical sectional view taken at right angles to Fig. 2, and on the line 3—3 of Fig. 1; Fig. 4 is a cross-sectional view on the line 4—4 of Fig. 2; Fig. 5 is a front elevation of the insulating sleeve or bushing inclosing the socket terminals; Fig. 6 is a vertical sectional view showing another manner of connecting the electrodes; and Fig. 7 is a top plan view thereof.

The outside metal container or casing is preferably stamped from sheet metal, the front member 2 being a flat rectangular piece with the lower end bent to form the bottom 2^a; and the rear member being bent into a trough or square-angle V-shape forming the back 3 and sides 3^a, the upper edge having inwardly extending ears or lugs 3^b which are provided with threaded openings to receive the screws 4 by which the top member 6 is secured. The latter is preferably formed of hard rubber or other suitable insulating material and is provided with apertures through which the plug contacts 7 project and are provided with depending contact members 8 which are adapted to

contact respectively with the electrode plates 10 and 12.

A bar 15 is soldered, welded, or otherwise integrally secured to the outer side of the front plate 2 and is provided with upper 60 and lower channels 17, 17^a having lateral branches which register with apertures in the plate 2. A spout 20 is threaded or otherwise secured to the upper end of the bar in connection with the passage 17 and an annular connection, which may be formed of two parts 21, 21^a is threaded to the lower end of the bar 15 and in connection with the passage 17^a, the outer end of the part 21^a being threaded to engage a threaded aperture 70 in the adjustable block 25 of the clamp by which the water heater is attached to a faucet. One form of my attachment clamp is illustrated in Figs. 1 and 2 and comprises a yoke member 26 having a stationary pin 75 or pointed stud 27 in one yoke arm and an adjustable screw 28 threaded in the other arm, whereby the yoke member may be clamped to a faucet 30. The adjustable supporting member 25 may then be forced upwardly by turning the screw 31 to bind the gasket 32 tightly against the lower edge of the faucet.

The electrodes consist of rectangular plates 10 and 12 of charcoal, carbon, graphite or other suitable material through which an electrolytic action may be obtained and which will not be decomposed. The plate 12 is provided with apertures 12^a adjacent the upper and lower ends which register with the apertures in the plate 2 and the passages 17, 17^a.

When the parts are assembled a sheet of rubber 40 is first placed against the inner surface of the front casing plate 2 and is provided with apertures which align with the apertures in the plate leading into the passages 17, 17^a. The electrode plate 2 is then laid against the rubber sheet 40 and over this is placed a rubber sheet 41 having 95 the entire central portion cut out so as to leave only, a narrow margin forming a frame around the four sides, as clearly indicated in Fig. 3. When the other electrode 100 105 110 115 120 125 130 135 140 145 150 155 160 165 170 175 180 185 190 195 200 205 210 215 220 225 230 235 240 245 250 255 260 265 270 275 280 285 290 295 300 305 310 315 sheet 45 is placed upon the opposite side of the electrode 10, after which the parts are surrounded by the shell casing member 3 which is securely clamped to the front plate 2 by means of bolts 46. When the insulating top member 6 is secured in position by means of the screws 4, the contact plugs 7 will be brought into electrical connection with the electrodes by the engagement of 10 the depending contact strips 8.

I have found it convenient to assemble the electrodes and secure them together to form a unit, and to provide each electrode with a projecting connecting wire, so that this unitary structure may be readily inserted in the casing. For this purpose I groove the top and bottom ends of the electrode plates, as indicated at 10^a, in Figs. 6 and 7, and pass a conductor wire 55, around the edge of the plates, the grooves holding them in position, and twist the free upper ends together to form terminals, which may be inserted in the hollow terminal connectors 7, as shown in Fig. 6. After placing the two plates together with the insulating marginal frame packing member 41, interposed to form the inner heating chamber 43, these parts may be held together as a unit by coating the edges with shellac varnish, the shellac coating over the wire 55, also forming an insulating protective covering. By thus binding the electrodes and interposed rubber separating-frame into a unit, and with the connecting wires surrounding each plate having their projecting ends twisted for insertion into the connectors, the work of assembling the heaters is greatly facilitated.

Any suitable socket may be employed to connect the heater with the socket of any 40 electric light fixture or other conductors connected with an electric source. For this purpose I have provided a terminal connecting device which is thoroughly insulated and when connected to the heater leaves no 45 connecting member exposed. This terminal connecting member comprises a hard rubber terminal socket 50 provided with apertures to receive the socket terminals 51 to which the ends of the flexible conductors 52 are 50 secured, an intermediate flexible rubber sleeve 53 and an outer hard rubber ferrule 54. As previously stated, this insulating terminal member completely incases the conductors and when in position on the heater, 55 leaves no exposed conducting wires.

The operation of the heater will be understood from the foregoing description of the parts, and is as follows:—

As the water enters the chamber 43 from 60 the inlet passage 17^a, it is spread out into a comparatively thin sheet which is easily heated by the passage of the electric current from one electrode plate 10 to the other plate 12, the water forming the conduct- 65 ing medium between the plates. The tem-

perature of the water flowing out through the spout 20 may be varied and easily regulated by causing the water to flow with greater or less rapidity, determined by the amount the spigot is turned. Inasmuch as 70 the water chamber 43 is entirely inclosed by the inner walls of the electrodes and by the surrounding rubber frame 41, while the electrodes are completely insulated from the outer metal casing, there can be no electrolytic action between the water and the metal casing as may be the case where the water is contained in a metal reservoir or casing with the electrodes immersed therein. The electrodes of carbon or graphite are not decomposed or electrolytically affected by the 80 passage of the current and are, therefore, practically indestructible. When the water is turned off, the small amount of water remaining in the chamber 43 is quickly 85 evaporated by boiling so that the electrical connection between the electrodes is interrupted and the flow of electric current thus automatically ceases. My electric heater is thus self-regulating and automatic in its 90 action and does not require the use of auxiliary fuses or other current protectors which are necessary with prior devices in order to protect the electric heating coils from being burned out in case the flow of 95 water is cut off.

The extreme simplicity of the heater and the parts which enter into its construction will be appreciated by those who are familiar with electric water heaters and its indestructibility and the automatic regulation of the current which ceases to flow when the water is shut off, thereby permitting the heater to be continuously connected to the electric supply if desired, will be especially 100 appreciated by those who have been subjected to the annoyance and expense attendant upon the use of prior devices which are liable to be burned out in case the water was accidentally turned off without simultaneously cutting off the electric current. I have described the construction illustrated in the accompanying drawing in detail for the purpose of clearly disclosing an embodiment of my invention but it will be evident 110 to engineers that various changes and modifications may be made within the scope of my claims and without in any manner departing from my invention. I have shown the heater provided with a single pair of electrodes, but in case it is desired to increase the capacity in larger heaters, a number of such pairs of electrodes may be employed, the plates being connected in parallel so as to increase the current-carrying 120 surface or capacity.

I claim:—

1. An electric fluid heater, comprising a casing or container provided with inlet and outlet openings, electrode plates within said 130

- casing and insulated therefrom, and an insulating packing frame separating said plates and forming a liquid-tight joint around the margins thereof to thereby form a chamber 5 between the electrodes, one of said electrode plates having openings adapted to aline with said openings in the casing.
2. An electric fluid heater, comprising a casing or container provided with inlet and 10 outlet openings, non-metallic electrode plates within said casing and insulated therefrom, an insulating packing frame separating said plates and forming a liquid-tight joint around the margins thereof to thereby form 15 a chamber between the electrodes, one of said electrode plates having openings adapted to aline with said openings in the casing, and tubular inlet and outlet members connecting respectively with the openings in the casing.
- 20 3. An electric fluid heater, comprising a casing having separable front and rear parts, one of said parts being provided with inlet and outlet openings, carbonaceous electrode plates clamped between said casing 25 parts with insulating means interposed between the plates and said parts, an insulating marginal packing separating said plates and thereby forming an inclosed heating chamber, one of the plates having openings 30 alining with said openings in the casing, and means adapted to form electrical connections with said plates.
4. An electric fluid heater, comprising a casing having separable front and rear parts and provided with means for clamping 35 them together, one part comprising a rectangular plate having one end bent inwardly to form the bottom of the casing and having inlet and outlet openings, the other part comprising a rectangular plate having its 40 sides bent to form the sides of the casing, carbonaceous electrode plates clamped between said casing parts with interposed insulating means therebetween, and an insulating marginal packing separating said 45 plates to thereby form an inclosed heating chamber, one of the plates having openings alining with said openings in the casing.
5. In an electric fluid heater as defined in claim 3, a separable member forming the 50 top of the casing and provided with contact devices adapted to connect with the electrode plates.
6. In an electric fluid heater as defined in claim 4, a separable member forming the 55 top of the casing and provided with contact devices adapted to engage the electrode plates, and a clamping device provided with a passage or channel in communication with the inlet opening and having means for attachment to a faucet.

In testimony whereof I affix my signature.

MILTON H. SHOENBERG.
